SELF-CONTAINED FLOWMETER

Gilbert J. Butterworth, Houston, Tex., and Stephen W. Gurasich, Lafayette, La., assignors to Sperry-Sun Well Surveying Company, Philadelphia, Pa., a corporation of Delaware

Original application October 2, 1951, Serial No. 249,332, now Patent No. 2,713,261, dated July 19, 1955. Divided and this application May 17, 1955, Serial No. 508,944

5 Claims. (Cl. 73—155)

This invention relates to well testing apparatus and, more particularly, to a self-contained flowmeter for measuring the subsurface flow of liquid in a well. This application is a division of our copending patent application Serial No. 249,332, filed October 2, 1951, now issued as Patent No. 2,713,261.

In obtaining crude petroleum, the pressure within the producing horizon usually decreases so that it is necessary to cause oil flow to adjacent wells by introducing water under pressure to the oil-bearing strata through former oil wells selected near the producing field. In some fields, water-bearing sands which overlie the oil strata are the source from which water is permitted to flow downwardly into the oil reservoir to create the necessary pressure by building up a hydrostatic head proportionate to the depth of the water in the field. The water flow used to create pressure in the oil-bearing strata must be carefully measured to avoid overflooding of the oil fields, and, consequently, losing the oil residue.

There are also numerous producing wells from which the flow of oil emerges at a relatively slow rate. There are also wells in which water is rising upwardly through the well from a water-bearing strata to an overlying oil-bearing strata. In these two types of wells it is frequently desirable to measure the flow of liquid, water or oil rising in the well.

It is an object of the present invention to provide a portable apparatus which may be lowered into a well and which will measure the rate of liquid flow in the well.

It is a further object of this invention to provide an apparatus which may be lowered into a well and provide a measurement of liquid flow therein without necessitating the use of any apparatus permanently mounted within the well.

The present apparatus is particularly adaptable to measuring relatively small rates of flow in that wells having low flow rates of either oil or water generally do not warrant the installation of permanent apparatus for providing flow measurement.

These and other objects of the invention will become apparent from the following description when read in conjunction with the accompanying drawings, in which:

Figures 1A and 1B are, respectively, longitudinal sections through the lower and upper portions of a flowmeter embodying the invention; and

Figure 2 shows a typical record produced by the apparatus shown in Figures 1A and 1B.

In the figures there is shown a sleeve 102 within which there is mounted a housing 104 by means of the fin members 106. The housing 104 is closed by a lower cap member 108 and an upper cap member 111. The cap member 111 is provided with a ring 111' for attachment of a cable or other lowering means.

An impeller member 112 which mounts impeller blades 114 is rotatably mounted on a pin 116 mounted in a stud 117 threaded into the lower fin group 106. Extending

2

from the upper end of the impeller member is a shaft 118 which passes through the cap 108 and has mounted on its upper end a cam 110 in an oil filled chamber 110'. The anti-friction bearings 105, the sealing glands 103 and the oil filled chambers 115 and 110' are provided in order that the impeller and the shaft 118 may rotate freely without leakage of well fluids into the chamber 115, the housing 160 being sealed at 170.

Mounted within the upper portion of the housing 104 is a clockwork mechanism generally indicated at 120. This mechanism is identical with the mechanism described in the application mentioned above and need not be described in detail herein, it being sufficient to note that the mechanism is in an inverted position with

15 respect to the position of the mechanism described in the above-mentioned application. The clockwork mechanism 120 is contained within a sleeve 124 and has at its upper end a knob 126 for use in winding the clock.

Affixed to the sleeve 128 which is rotated by operation of the clockwork mechanism is means for mounting a record member 130 which is indicated generally by the numeral 100 in Figure 2 in which it is shown in plan form. Also attached to the sleeve 128 is an insulated cam 132.

25 An electro-chemical recording is produced on the record member 130. This record member preferably comprises a sheet of paper containing a colored material such as a colored metallic ferrocyanide which, upon the passage of an electric current while it is moist, will be 30 marked with a white spot by reason of the formation of alkali at a cathode provided by a metallic point 142 hereinafter described.

35 Mounted on a plate 134 supporting the clockwork mechanism is a contact mounting block 138 which is formed of an insulating material and mounts a contact arm 136. The upper end of the contact mounting arm 136 supports a cam follower 140 which is adapted to engage the raised portion of the insulated cam 132. Also mounted on the upper end of the contact arm 136 is a 40 contact point 142 which engages the record member when the reduced diameter portion of the cam 132 is beneath the cam follower 140 as shown in the drawing. As previously described, the member 128 rotates as the clockwork mechanism operates and, therefore, by selecting 45 the extent of the periphery of the cam 132 over which the contact 142 is permitted to engage the record member 130, the time interval of contact may be established, thus establishing the time interval of recording.

Attached to the lower end of the contact arm 136 is 50 a current limiting resistor 144 and extending from the resistor is a conductor 146 which is connected to the contact member 148.

Attached to the sleeve member 124 is a coupling member 150 which is adapted to house a plurality of batteries 55 152 stacked in series relationship with the negative poles upward. The upper end of the coupling 150 contains insulated plug members 154 which support contact members 148 and 156 which are electrically connected and mechanically separated by means of a spring 158.

60 The lower end of the coupling member 150 is coupled to a sleeve 160 and mounts an insulated block 162 through which there is extended a contact pin 164.

65 Mounted in the lower end of the sleeve 160 is a member 166 through which extends a bolt 168 which is insulated from the block 166 by means of members 170. The bolt 168 has mounted to its lower end a contact finger 172 which is adapted to be contacted by the rise of the cam 110 as the impeller member 112 is rotated.

In the operation of this invention the upper cap 111 and the spring 109 are removed from the housing 104 and the sleeve member 124 and the clockwork mech-

anism removed therefrom. Sleeve 124 is removed from the coupling 150 and a record strip 130 is positioned on the sleeve 128. The knurled head of the clock 126 may then be wound to provide operation of the clockwork mechanism for the desired period of time and the apparatus reassembled with batteries in position. The spring 109 urges the cap 125, the sleeve member 124 and the successive elements attached to the lower portion of the sleeve member 124 downwardly in order that the member 166 is held firmly in engagement with the shoulder 167 of the housing 104.

With the parts thus assembled, the flowmeter may be lowered into a well to the depth at which it is desired to measure the rate of flow. The impeller member 112 and the cam 110 will rotate immediately upon being subjected to the passage of fluid within the well. However, the electrical circuit through the record strip is interrupted by the open contact member 142, the cam follower 140 being at this time in engagement with the insulated cam 132.

After the expiration of a predetermined time interval during which the sleeve 128 is rotated by the clockwork mechanism the rise of the cam 132 mounted on the sleeve 128 will pass from beneath the cam follower 140 and permit the contact arm 136 to drop downwardly with the contact 142 in engagement with the record strip 130. The electrical circuit is now completed from the batteries 152 through the contact members 156, 143, conductor 146, resistor 144, contact arm 136, contact point 142, and record strip 130 to ground through the clockwork mechanism. The return circuit from the clockwork mechanism is through the sleeve 124 and the housing 104 to the impeller shaft 118, the cam 110 and the contact 172 each time the rise of the cam 110 engages the contact 172, through the bolt 168 and the contact pin 164 to the batteries 152.

Thus it will be apparent that no current can pass from the batteries to the record strip until the clockwork mechanism has operated for a sufficient period of time to carry the rise of the cam 132 clear of the cam follower 140, thereby permitting the contact 142 to engage the record strip 130. When this condition exists current will pass each time the rise of the cam 110 engages the contact 172. Thus there is provided on the record strip 130 a plurality of dots 131, the spacing of which or the number occurring during the recording interval being determined by the rate of operation of the clockwise mechanism and the speed of rotation of the impeller. The cam 132 has only a portion of its periphery depressed and, therefore, after a predetermined recording time interval has passed, the contact 142 will be raised from the record member. The number of dots appearing on the record member during the recording interval, 143 in Figure 2, is indicative of the rate of rotation of the impeller member 112 and, therefore, of the rate of flow past the impeller member.

As indicated hereinabove, when the instrument is lowered into a well, the cam follower 140 is in engagement with the cam 132 and the contact member 142 is open. It will be evident, therefore, that the cam 132 operates to afford a time delay before, and another after, a predetermined recording time interval, which time delays are provided to allow time for lowering the instrument into and removing it from the well. In the form of the invention illustrated, one measurement is made on a record strip during the predetermined recording time interval.

It will be evident that in the operation of this form of the invention the assembled apparatus may be lowered into a well to a desired level therein and the operator with a clock at the surface of the earth will be able to determine when the recording interval begins and ends. After the recording has been completed, the operator may withdraw the apparatus from the well and by ex-

amination of the record strip determine the flow rate at that level.

While the clockwork mechanism referred to as employed in the disclosed embodiment of the invention is described as being similar to that employed in the above-mentioned application, it will be evident that various types of clockwork mechanisms may be employed for driving a member such as the sleeve 128 on which there is adapted to be mounted a record strip and a cam in order to provide a pulse register operative for a predetermined time interval.

While the apparatus may be operated without the external sleeve member shown in the drawing, this member not only affords protection for the impeller but also makes possible the use of the flowmeter in casings of various sizes with results of reasonable accuracy. The invention disclosed herein provides a simple and practical means for periodically determining the flow rates either upwardly or downwardly at any locations within a well without the necessity of any apparatus being permanently installed in the well.

What is claimed is:

1. A flowmeter for determining the rate of flow of a liquid through a well bore hole comprising a tubular housing adapted to be lowered into a bore hole, a shaft revolvably journaled in the lower end portion of said housing, an impeller mounted upon said shaft externally of said housing, a revoluble member in the upper end portion of said housing, a record strip mounted upon said revoluble member and adapted for being marked by electric current passed therethrough, a constant speed motor for actuating said revoluble member and the record strip mounted thereon, a first element adapted for making contact electrically with said record strip, means actuated by said revoluble member for holding said first contact element disengaged from said record strip for a predetermined time interval sufficient for lowering the flowmeter into the hole, engaged with said record strip for a predetermined recording time interval, and then disengaged from said record strip for a predetermined time interval sufficient for removing said flowmeter from the hole, a second contact element, said shaft being adapted for intermittently making contact electrically with said second contact element as said shaft revolves, and means series connecting said first contact element, record strip, second contact element and shaft in electric circuit, the latter being closed intermittently during the predetermined recording time interval thereby to pass electric current through said record strip for marking the same.

2. A flowmeter as defined in claim 1 wherein the lower end portion of the housing is provided with impeller shaft accommodating means operative for securing said housing against ingress of well fluids, said means including a chamber within said housing filled with a dielectric fluid and housing the upper end portion of said shaft and the second contact element.

3. A flowmeter as defined in claim 2 wherein the upper end portion of the impeller shaft mounts a cam operable by said shaft for engaging the second contact element at intervals dependent upon the rate at which said shaft is rotated.

4. A flowmeter for determining the rate of flow of liquid through a well bore hole comprising a housing adapted for being lowered into the bore hole, an impeller carried by said housing, means rotatably mounting said impeller in a position to be rotated by liquid flowing longitudinally through the bore hole, a record member within said housing adapted for being marked by electric current passed therethrough, a first element adapted for making contact electrically with said record member, means for moving the latter and said first contact element continuously relative to, and in contact with, one another during a predetermined recording time interval, a second contact element, said impeller mounting means being

adapted for intermittently making contact electrically with said second contact element when said impeller is rotating, means series connecting said first contact element, record member, second contact element and impeller mounting means in electric circuit, said second contact element being operative intermittently during said predetermined recording time interval, when disposed in contact with said impeller mounting means, for closing said circuit and thereby passing current through said first contact element and record member for marking the latter, and operative, when disengaged from said impeller mounting means, for opening said circuit and thereby interrupting the flow of current through said first contact element and recording member.

5. A flowmeter for determining the rate of flow of liquid through a well bore hole comprising a housing adapted for being lowered into the bore hole, an impeller carried by said housing, means rotatably mounting said impeller externally of said housing in a position to be rotated by liquid flowing longitudinally through the bore hole, a record member within said housing adapted for being marked electrochemically by electric current passed therethrough, a first element adapted for making contact electrically with said record member, means for moving the latter and said first contact element continuously at

15 20 25

a constant speed relative to, and in contact with, one another during a predetermined recording time interval, a second contact element, said impeller mounting means being adapted for intermittently making contact electrically with said second contact element when said impeller is rotating, means series connecting said first contact element, record member, second contact element and impeller mounting means in electric circuit, said second contact element being operative intermittently during said predetermined recording time interval, when disposed in contact with said impeller mounting means, for closing said circuit and thereby passing current through said first contact element and record member for marking the latter, and operative, when disengaged from said impeller mounting means, for opening said circuit and thereby interrupting the flow of current through said first contact element and recording member.
